DESIGN FOR A FISHING BAIT

Philip Porter Dalton, Tampa, Fla.

Application June 3, 1939, Serial No. 85,327

Term of patent 14 years

To all whom it may concern:

Be it known that I, Philip Porter Dalton, a citizen of the United States, residing in Tampa, in the county of Hillsborough and State of Florida, have invented a new, original, and ornamental Design for Fishing Baits, of which the following is a specification, reference being had to the accompanying drawing, forming part thereof, in which

Figure 1 is a top plan view, Fig. 2 a side elevation, Fig. 3 a bottom view and Fig. 4 a front end view of a fishing bait showing my new design.

I claim:

The ornamental design for a fishing bait, as shown.

P. P. DALTON.
